[57] CLAIM

The ornamental design for a pet dinette, substantially as shown and described.

DESCRIPTION

FIG. 1 is an isometric view taken from the top, front and left side of a pet dinette showing my new design;
FIG. 2 is a left side elevational view thereof;
FIG. 3 is a top plan view thereof;
FIG. 4 is a right side elevational view thereof;
FIG. 5 is a front elevational view thereof; and
FIG. 6 is another isometric view taken from the top, and front and left side thereof showing the pet dinette in a partial closed position.
